(57) **CLAIM**

The ornamental design for a coupler, as shown.

DESCRIPTION

FIG. 1 is a perspective view of the coupler of the invention;
FIG. 2 is a side elevational view of the coupler;
FIG. 3 is an opposite side elevational view of the coupler;
FIG. 4 is an end elevational view of the coupler, the opposite
end elevational view being a mirror image thereof;
FIG. 5 is a top plan view of the coupler; and,
FIG. 6 is a bottom view of the coupler.
